PAPER BOTTLES AND THE LIKE AND METHOD OF MANUFACTURE

James E. Annen, Kalamazoo, Mich., assignor to
Sutherland Paper Company, Kalamazoo, Mich.

Application March 6, 1943, Serial No. 478,225

11 Claims. (Cl. 93—39.1)

1

This invention relates to improvements in paper bottles and the like, and method of manufacture.

The main objects of this invention are:

First, to provide a paper bottle or container well adapted for use as a milk bottle which may be formed entirely of paper stock and is well adapted to receive and retain a closure of the disk type.

Second, to provide a container having these advantages which may be formed of relatively light stock and at the same time is strong and rigid.

Third, to provide a structure having these advantages which is economical to produce.

Fourth, to provide a method of manufacturing containers of the type described which enables very large production by machinery.

The accompanying drawings illustrate both the steps of manufacture and the completed container.

Fig. 1 is a blank from which the wall or body is formed.

Fig. 2 is a side elevation of the formed wall of the body.

Fig. 3 is a fragmentary side elevation illustrating the two steps succeeding the forming of the body, namely, the forming of a flange on the upper end of the body and the application of glue thereto.

Fig. 4 is a fragmentary side elevation illustrating the step of inserting a top member within the container wall.

Fig. 5 is a fragmentary side elevation showing the structure after the top member has been beaded or crimped over the rim on the body member.

Fig. 6 is a top view of the structure as shown in Fig. 5.

Fig. 7 is a top view after the central portion of the top member has been punched out to provide a supporting flange or ridge for the closure.

Fig. 8 is a fragmentary vertical section after the bottom has been inserted and secured.

Fig. 9 is a fragmentary longitudinal section illustrating one means for forming the flange on the upper end of the container wall or body.

Fig. 10 is a fragmentary view partially in longitudinal section illustrating another means for forming the flange on the wall or body member.

Fig. 11 is a fragmentary section illustrating suitable mechanism for crimping or clamping the top member, showing in retracted position the means for securing the top member to the wall or body member and the punching out of the central portion of the top member.

Fig. 12 is a fragmentary view of the parts shown in Fig. 11 in actuated position.

Fig. 13 is an enlarged fragmentary vertical

section illustrating the completed top portion of the structure with a closure disk in position.

Fig. 14 is a perspective view of a top member prior to its application to the body or wall member.

Fig. 15 is a perspective view of the blank from which the bottom of the container is formed.

Fig. 16 is a view of the completed container partially in vertical section and partially broken away.

In the accompanying drawings the invention is illustrated as it has been embodied and practiced in the manufacture of milk bottles, although it will be understood that the container of this invention is adapted for a wide variety of uses.

The conical tubular body or wall member 1 is formed of a suitable blank 2 having adhesive 3 applied to one edge thereof, the edges of the blank being brought together into lapping relation and sealed throughout. For some purposes a thermoplastic adhesive may be desirable. After forming the blank the next step in the method is the forming of the flange 4 on the upper end thereof.

In production it is preferable to employ a suitable conveyor having a series of tubular conical mandrels 5 thereon, these mandrels having an internally cylindrical portion 6 at their upper ends. The mandrel also constitutes a die member, as will be pointed out. The mandrels are of such size as to effectively support the wall or body members 1 and the sleeves thereon with their upper ends projecting above the mandrels.

The flange 4 is formed by turning the same outwardly as by means of the forming member or die member 7 having an annular curved recess 8 at its lower end. However, the flange may be formed by a rolling or spinning operation, a spinning member 9 being shown in Fig. 10.

After the flange is formed an adhesive sealing material is applied thereto and the cup-shaped top member 10 formed of suitable paper or fibrous stock is inserted therein as shown in Fig. 11, with the end of the mandrel in supporting relation to the top member below its cylindrical side walls.

In this position the top member projects above the flange on the body member. The forming member 11 is then actuated, this forming member having a reduced tip portion 12 adapted to enter and supportingly fit within the wall of the

top member and an annular downwardly facing curved channel 13 which gradually crimps or turns the projecting edge of the top member around the flange 4 into clamping retaining engagement therewith. The flange is also curved during this operation as shown in Fig. 13. This step is performed before the adhesive sealing material has set and it spreads and brings the adhesive material into thoroughly complete sealing and adhering relation to these two parts.

Associated with the forming member is a punch

14 which is actuated in timed relation to the actuation of the forming member so that after the forming member is completely actuated the punch is actuated to punch out the central portion 15 of the top member. The top member is effectively clamped in position during this punching operation so that it is not distorted. As stated, the mandrel performs the double function of a mandrel and female die member. This operation forms a supporting ledge or flange 16 for a disk-like type of closure 17 as shown in Fig. 13.

It will be noted that there is a slight space or clearance shown at 18 in Fig. 13 between the cylindrical side portion of the top member and the conical wall of the container which permits some springing or expanding of the top member adjacent the closure supporting seat thereof when the closure disk is forced or pushed into position. I have not attempted to illustrate this springing action as it would be relatively slight where all parts are made in proper proportion, but it is of decided advantage in the effective retaining of the closure and in accommodating closures varying in diameter.

After the top member has been applied to the wall the bottom 28 is applied. This is formed from a disk 19 of fibrous material, see Fig. 15. A flange 20 is formed on the disk and the bottom thus formed is inserted in the lower end of the container. The bottom wall is then crimped or folded around the flange 20 as shown at 21. Adhesive is preferably used at the joint in this operation. The means for applying the bottom are not illustrated as suitable mechanisms for performing this operation are known in the art.

Suitable waterproofing may be applied if desired, paraffin being quite commonly used.

The method of this invention can be very economically practiced, that is, a fairly simple machine may be used with substantial and uniform production. The container is strong and rigid, the top member effectively reinforcing the wall or body member as well as providing a suitable rim and a closure seat. The structure illustrated is designed as a milk bottle or like container of the conical type, but it will be understood that other forms of containers or closures may be made, and containers adapted for various uses. It is believed that the disclosure made will enable those skilled in the art to embody or practice the invention as may be desired.

Having thus described the invention what is claimed as new and desired to secure by Letters Patent is:

1. The method of making milk bottles and like containers of fibrous material adapted to receive a closure disk comprising the steps of forming a tubular conical wall of fibrous material, forming an out-turned substantially flat flange on the upper edge thereof, applying an adhesive sealing material to said flange, inserting a cup-shaped top member of fibrous material in the upper end of said wall with a portion of the side wall thereof projecting above the said wall flange, supporting said top member against axial movement by a tubular conical die and mandrel member supportingly fitting within said wall member and supporting said top member below the side wall portion thereof, crimping the projecting portion of the side wall of said top member around said flange on said wall prior to the drying of the adhesive sealing material and simultaneously curving said flange downwardly and clamping said top member into embracing relation thereto whereby the top member constitutes a curved rim

and a reinforcing member for the wall of the container, punching out the central portion of said top member to provide an inwardly projecting flange adapted to support a disk-like closure, and thereafter securing a bottom of fibrous material within the wall of the container.

2. The method of making milk bottles and like containers of fibrous material adapted to receive a closure disk comprising the steps of forming a tubular conical wall of fibrous material, forming an out-turned substantially flat flange on the upper edge thereof, applying an adhesive sealing material to said flange, inserting a cup-shaped top member of fibrous material in the upper end of said wall with a portion of the side wall thereof projecting above the said wall flange, supporting said top member against axial movement by a tubular conical die and mandrel member supportingly fitting within said wall member and supporting said top member below the side wall portion thereof, crimping the projecting portion of the side wall of said top member around said flange on said wall prior to the drying of the adhesive sealing material and simultaneously curving said flange downwardly and clamping said top member into embracing relation thereto whereby the top member constitutes a curved rim and a reinforcing member for the wall of the container, and punching out the central portion of said top member to provide an inwardly projecting flange adapted to support a disk-like closure.

3. The method of making milk bottles and like containers of fibrous material adapted to receive a closure disk comprising the steps of forming a tubular conical wall of fibrous material with an out-turned flange on the upper edge thereof, applying an adhesive sealing material to said flange, inserting a cup-shaped top member of fibrous material in the upper end of said wall with a portion of the side wall thereof projecting above the said wall flange, supporting said wall and top member against relative axial movement by a tubular conical die and mandrel member supporting said top member below the side wall portion thereof, crimping the projecting portion of the side wall of said top member around said flange on said wall into embracing relation thereto whereby the top member constitutes a curved rim and a reinforcing member for the wall of the container, punching out the central portion of said top member to provide an inwardly projecting flange adapted to support a disk-like closure, and thereafter securing a bottom of fibrous material within the wall of the container.

4. The method of making milk bottles and like containers of fibrous material adapted to receive a closure disk comprising the steps of forming a tubular conical wall of fibrous material with an out-turned flange on the upper edge thereof, applying an adhesive sealing material to said flange, inserting a cup-shaped top member of fibrous material in the upper end of said wall with a portion of the side wall thereof projecting above the said wall flange, supporting said wall and top member against relative axial movement by a tubular conical die and mandrel member supporting said top member below the side wall portion thereof, crimping the projecting portion of the side wall of said top member around said flange on said wall into embracing relation thereto whereby the top member constitutes a curved rim and a reinforcing member for the wall of the container, and punching out the central portion of said top member to provide an inwardly

projecting flange adapted to support a disk-like closure.

5. The method of making containers of fibrous material adapted to receive a closure disk comprising the steps of forming a tubular wall of fibrous material, forming an out-turned substantially flat flange on the upper edge thereof, applying an adhesive sealing material to said flange, disposing a cup-shaped top member of fibrous material in the upper end of said wall with a portion of the side wall thereof projecting above the said wall flange, crimping the projecting portion of the side wall of said top member around said flange on said wall prior to the drying of the adhesive sealing material and simultaneously curving said flange downwardly and clamping said top member into embracing relation thereto whereby the top member constitutes a curved rim and a reinforcing member for the wall of the container, and punching out the central portion of said top member to provide an annular inwardly projecting flange adapted to support a disk-like closure.

6. The method of making containers of fibrous material adapted to receive a closure disk comprising the steps of forming a tubular wall of fibrous material with an out-turned flange on the upper edge thereof, applying an adhesive sealing material to said flange, disposing a cup-shaped top member of fibrous material in the upper end of said wall with a portion of the side wall thereof projecting above the said wall flange, crimping the projecting portion of the side wall of said top member around said flange on said wall whereby the top member constitutes a curved rim and a reinforcing member for the wall of the container, and punching out the central portion of said top member to provide an annular inwardly projecting flange adapted to support a disk-like closure.

7. The method of making containers of fibrous material adapted to receive a closure disk comprising the steps of forming a tubular wall of fibrous material, forming an out-turned substantially flat flange on the upper edge thereof, applying an adhesive sealing material to said flange, disposing a cup-shaped top member of fibrous material in the upper end of said tubular wall, said top member having a vertically disposed edge portion of the side wall thereof projecting above the said tubular wall flange, and crimping said projecting vertically disposed edge portion of the side wall of said top member around said flange on said tubular wall prior to the drying of the adhesive sealing material and simultaneously curving said flange downwardly and clamping said top member into embracing relation thereto whereby the top member constitutes a curved rim and a reinforcing member for the wall of the container, and supporting said cup-shaped top member against inward thrust during the crimping and clamping operations, the supporting of said top member being by supportingly engaging the bottom thereof independently of and within said tubular wall.

8. The method of making containers of fibrous material adapted to receive a closure disk comprising the steps of forming a tubular wall of fibrous material with an out-turned flange on the upper edge thereof, applying an adhesive sealing material to said flange, disposing a cup-shaped top member of fibrous material in the upper end of said tubular wall, said top member having a

vertically disposed edge portion of the side wall thereof projecting above the said tubular wall flange, and crimping said projecting vertically disposed edge portion of the side wall of said top member around said flange on said wall whereby the top member constitutes a curved rim and a reinforcing member for the wall of the container, and supporting said top member against inward thrust during the crimping operation, the supporting of the top member being by supportingly engaging the bottom thereof independently of and within said tubular wall.

9. The method of making containers of fibrous material adapted to receive a closure disk comprising the steps of forming a tubular conical wall of fibrous material with an out-turned flange on the upper edge thereof, applying an adhesive sealing material to said flange, disposing a top member of fibrous material having a cylindrical side wall in the upper end of said container wall with a portion of the top member side wall projecting above said wall flange, crimping the projecting portion of the side wall of the top member around the flange on said wall prior to the drying of the adhesive sealing material, said top member being provided with an annular closure seat at its inner end, the cylindrical wall of the top member being spaced from the conical wall of the container to provide an annular space between the cylindrical wall of said top member and the conical wall of the container for permitting expansion of the inner end of the top member when a closure is pressed therein, and supporting said top member against inward thrust during the crimping operation, the supporting of the top member being by supportingly engaging the bottom thereof independently of and within said tubular wall.

10. A container of fibrous material adapted to receive a closure disk comprising a tubular wall member of fibrous material having an out-turned flange at its upper end, an annular top member of fibrous material disposed within the upper end of said wall member, said top member being crimped around said flange into closely embracing relation thereto, there being adhesive and sealing material between said flange and said top member, said top member having an opening through its inner end surrounded by an annular flange constituting a closure seat, the lower end portion of the side wall of said top member being spaced from said tubular wall to provide expansibility of the top member relative to the container wall when a disk-like closure of predetermined diameter is disposed therein.

11. A container of fibrous material adapted to receive a closure disk comprising a conical wall member of fibrous material having an out-turned flange at its upper end, an annular top member of fibrous material disposed within the upper end of said wall member, said top member being crimped around said flange into closely embracing relation thereto, said top member having an opening through its inner end surrounded by an annular flange constituting a closure seat, the side wall of said top member being cylindrical to provide an annular space between the lower end thereof and the conical wall to permit expansibility of the top member relative to the container wall when a disk-like closure of predetermined diameter is disposed therein.

JAMES E. ANNEN.
